US0D1071558S

(12) **United States Design Patent** (10) **Patent No.:** **US D1,071,558 S**
(45) **Date of Patent:** **** Apr. 22, 2025**

(54) **BIN**

(71) Applicant: **HAI ROBOTICS CO., LTD.**,
Guangdong (CN)

(72) Inventors: **Qiong Zhang**, Guangdong (CN);
Yongjian Wang, Guangdong (CN);
Jinrui Duan, Guangdong (CN)

(73) Assignee: **HAI ROBOTICS CO., LTD.**,
Guangdong (CN)

(**) Term: **15 Years**

(21) Appl. No.: **29/878,163**

(22) Filed: **Jun. 16, 2023**

(30) **Foreign Application Priority Data**

Dec. 19, 2022 (CN) 202230877703.8

(51) **LOC (15) Cl.** **09-04**

(52) **U.S. Cl.**

USPC **D3/304**

(58) **Field of Classification Search**

(57) **CLAIM**

The ornamental design for a bin as shown and described.

DESCRIPTION

FIG. 1 is a first perspective view of a bin;

FIG. 2 is a second perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is an enlargement view of the indicated portion shown in FIG. 1; and,

FIG. 10 is an enlargement view of the indicated portion shown in FIG. 2.

The dash-dash broken lines depict portions of the bin that form no part of the claimed design. The remaining long dash-dash broken lines in FIGS. 1-2 and 9-10 depict enlargement boundary limits that form no part of the claimed design.

1 Claim, 10 Drawing Sheets
